UNITED STATES PATENT OFFICE.

JAMES G. HARDY, OF NEW YORK, N. Y.

DESIGN FOR A TABLE COVER OR ARTICLE OF SIMILAR NATURE.

Application filed March 14, 1923. Serial No. 5,475. Term of patent 14 years.

To all whom it may concern:

Be it known that I, JAMES G. HARDY, a citizen of the United States, residing at New York, county and State of New York, have invented a new, original, and ornamental Design for Table Cover or Article of Similar Nature, of which the following is a specification, reference being had to the accompanying drawing, forming part thereof.

The figure is a plan view of a table cover, showing my new design.

It is intended that my design for a table cover or similar article may be made in any size desired.

I claim as my invention:—

The ornamental design for a table cover or article of similar nature, substantially as shown.

JAMES G. HARDY.
